(57) **CLAIM**

The ornamental design for refrigerated display case, as shown and described.

DESCRIPTION

FIG. 1 is a front perspective view of a refrigerated display case showing our new design;

FIG. 2 is a rear perspective view thereof;

FIG. 3 is a top perspective view thereof illustrating a shelf; and,

FIG. 4 is a bottom perspective view thereof illustrating a shelf.

The broken lines are for the purpose of illustrating the environment of the article only and form no part of the claimed design.

1 Claim, 3 Drawing Sheets

FIG. 1

FIG. 2

FIG. 3
